(57) **CLAIM**

The ornamental design for a height-adjustable work platform, as shown and described.

DESCRIPTION

FIG. 1 is a top, front, left perspective view of a height-adjustable work platform, showing my new design, in a first operating condition.

FIG. 2 is a front elevation view of the height-adjustable work platform of FIG. 1, shown enlarged for clarity of disclosure.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a top, front, left perspective view of a height-adjustable work platform, showing my new design, in a second operating condition.

FIG. 9 is a front elevation view of the height-adjustable work platform of FIG. 8, shown enlarged for clarity of disclosure.

FIG. 10 is a rear elevation view thereof.

FIG. 11 is a left side elevation view thereof.

FIG. 12 is a right side elevation view thereof.

FIG. 13 is a top plan view thereof; and,

FIG. 14 is a bottom plan view thereof.

The broken lines in the drawings depict portions of the height-adjustable work platform that form no part of the claimed design.
